UNITED STATES PATENT OFFICE.

JOSHUA ARTHUR BARBER LOMAX, OF BOLTON, WILLIAM TURNER AND JOHN TURNER, OF CHORLEY, AND JAMES BOOTH BENTLEY, OF CLAYTON-LE-WOODS, NEAR CHORLEY, ENGLAND.

SHUTTLE-CHECKING MECHANISM FOR LOOMS.

Application filed May 2, 1922. Serial No. 557,853.

To all whom it may concern:

Be it known that we, JOSHUA ARTHUR BARBER LOMAX, WILLIAM TURNER, JOHN TURNER, and JAMES BOOTH BENTLEY, subjects of the King of Great Britain, and residents, respectively, of Ravenhurst, Heaton, Bolton, in the county of Lancaster, England, 19 Mayfield Road, Chorley, in the same county, 14 Friday Street, Chorley, aforesaid, and Brownley Terrace, Clayton-le-Woods, near Chorley, aforesaid, have invented a certain new and useful Improvement in Shuttle-Checking Mechanism for Looms, of which the following description, 15 having reference to the accompanying sheets of drawings, is a specification.

It relates to means for checking shuttles when they arrive the shuttle boxes in looms whether same are of the fast reed or of the 20 loose reed type, and our said invention consists in the employment of devices which will efficiently attain the object desired and will also so guide and conduct the shuttle throughout its operations that the same is 25 caused to come in contact with the picker at all times by striking the said picker at one and the same place, thus a great saving in pickers is effected on account of avoiding the indentation of a large space on the 30 picker by the tip of the shuttle as is well understood. The precision with which the shuttle arrives at the same place within the shuttle box is such that new pickers may be mounted in position upon their picker spin- 35 dles and the loom started into action without necessitating the preparation or adjustment of said pickers to meet any actions of the tips of the shuttles from commencing with a new picker to the complete wearing 40 out of the same picker, since said tips of the shuttle at all times strike or come into contact with the same point or part of the picker with the results stated.

In the accompanying sheet of drawings 45 illustrative of our invention,

Fig. 1 is a front elevation of sufficient of the end of a slayboard or lay to show the

application thereto of our improved devices.

Fig. 2 is a plan of the parts shown by Fig. 1.

Fig. 3 is a view of the parts shown by Figs. 1 and 2 as seen from behind.

Fig. 4 is a sectional end elevation showing the application of our improved devices as is hereinafter explained.

Figs. 5 and 6 are perspective views of parts hereinafter more particularly described.

B indicates the slayboard or lay of the loom, C the hand rail and D the lay-sword.

In carrying our invention into effect we make use of a swell lever or swell device 2 at the front of the shuttle box 3 as well as a swell device (which is in the form of a swell lever) 4 at the rear of said shuttle box 3 on the slayboard B. The swell device 2 at the front of the shuttle box is situated at the entrance thereto as shown by Figs. 1 and 2 where it is operated or held in position by the tension of a spring 5 so that the incoming shuttle 6 will firstly come in contact with said device 2 in order that the actions of this swell device 2 may force the shuttle 6 against the straight surface of the back a of the shuttle box 3 by which means its path is secured in a direct or straight line until it moves forward within the shuttle box 3 to come into contact with the second swell lever 4 which is situated at the back of the shuttle box 3 as shown by Figs. 2 and 3. Said swell 4 is operated by the spring 7 in well known manner, but said spring 7 will permit the movement of the swell 4 by the actions of a less force than is required to move the swell 2.

By this arrangement of shuttle swells 2 and 4 the shuttle 6 is guided in the first part of its path within the shuttle box 3 by the front swell 2 and on reaching the swell 4 in the rear wall thereof any deflection that takes place has the effect of forcing the other end b of the shuttle 6 more firmly against the back wall a of the shuttle box 3 by which arrangement we have found that

the shuttle 6 at all times strikes the picker 8 in one and the same place throughout all of the useful period of working of said picker 8.

5 In making use of the devices 2 and 4 as described we have also found that on the shuttle 6 being picked or thrown out of the shuttle box 3 the guiding actions of the swell 4 at the back of the shuttle box in conjunction with the guiding actions of the swell 2 at the front have the effect of causing the leading end *b* of the shuttle to be directed towards the reed 10 and therefore said shuttle 6 is kept in its desired path with very little likelihood of being thrown out of same thus ensuring the arrival of the shuttle 6 in the shuttle box at the other end of the loom with great regularity as to its exact position therein.

22 The form of swell 2 which we prefer to make use of is of the grooved character shown by Figs. 4 and 5, while the front wall *d* of the shuttle box 3 is cut away to receive the parts *g* and *g*¹ of this swell 2 above and below the central part *h* of said wall *d* which remains intact.

This arrangement enables the swell 2 to slide within the guiding surfaces *k*, *k*¹ (see Fig. 6) adjoining the part *h* and at the same time affords space between the inner surfaces to permit the passage of the weft which is being paid out by the shuttle to enter and lie between same. The swell 2 may be of any suitable material or substance, but we preferably make same of wood since we find by so doing that its actions upon the wooden walls of the shuttles is less injurious.

When making use of the devices above described we have found that on account of the shuttle 6 coming in contact with the first swell 2 it is so checked in its movement that by moving forward to the second swell 4, the greater part of its force is broken, consequently only a very short check strap 11 mounted upon the picker spindle 12 for the picker 8 to contact with, is required and this check strap 11 is arranged to take over said picker spindle 12 and extend towards the back of the shuttle box 3 where we mount a spring 13 to keep it normally in its forward position to act as a slight buffer for the picker when it is propelled by the incoming shuttle 6, to its rearmost position as shown by Figs. 1 and 2.

55 The spring 5 which actuates the front swell may be used in conjunction with a sliding swell 2 as shown in the drawings and which we preferably make use of, but we may also make use of a hinged swell at the front of the shuttle box similar in character to the hinged swell 4 which we use at the back of the shuttle box.

Further than this the swell lever 4 may be of the character shown so that it may be used for actuating the stop rod of a loom

when our devices are used in connection with what is known as a "fast reed loom," while the other arrangements shown may be used in conjunction with what are known as a "loose reed loom."

Such being the nature and object of our said invention what we claim is:—

1. In shuttle checking mechanism for looms, a shuttle box, a swell mounted upon the front wall of the shuttle box near the entrance thereto, a spring for acting upon said swell, another swell mounted on the rear wall of the shuttle box, and further from the entrance to the box than said first mentioned swell, and a spring for actuating said rear swell, the portion of said box opposed to said last mentioned swell being substantially stationary to maintain a fixed home for the end of the shuttle approaching the outer end of the box.

2. In a shuttle checking mechanism for looms, a shuttle box, a swell reciprocably mounted upon the front wall of the shuttle box near the entrance thereto, a spring for acting upon said swell, another swell mounted on the rear wall of the shuttle box, and further from the entrance than said first mentioned swell, and a spring for actuating said rear swell, the portion of said box opposed to said last mentioned swell being substantially stationary to maintain a fixed home for the end of the shuttle approaching the outer end of the box.

3. In shuttle checking mechanism for looms, a shuttle box having openings extending through its front wall near the entrance thereto, a swell having spaced lugs extending through said openings, said swell spanning the portion of the front wall between said openings, and the lugs thereof having inclined surfaces for contact with the shuttle, there being a space between said surfaces, a spring for actuating said swell, another swell mounted in the rear wall of the box further from the entrance than said first mentioned swell, and spring means for actuating said last mentioned swell.

4. In shuttle checking mechanism for looms, a shuttle box having openings extending through its front wall near the entrance thereto, a reciprocable swell having spaced lugs extending through said openings, said swell spanning the portion of the front wall between said openings, and the lugs thereof having inclined surfaces for contact with the shuttle, there being a space between said surfaces, a spring for actuating said swell, another swell mounted in the rear wall of the box further from the entrance, and spring means for actuating said last mentioned swell.

5. In shuttle checking mechanism for looms, a shuttle box, having spaced openings formed in its front wall, a swell positioned adjacent the entrance to said box, and hav-

ing spaced means extending through openings in the front wall of the box, inclined surfaces on said means adapted to engage a shuttle, there being a space between said surfaces, a swell further within said box and extending through the rear wall thereof, the portion of said box opposite said last mentioned swell being substantially stationary to maintain a fixed home for the end of the

shuttle approaching the outer end of the 10 shuttle box, and spring means for actuating said swells.
